UNITED STATES PATENT OFFICE.

WILLIAM J. LAUSTERER, OF JAMESTOWN, NEW YORK, ASSIGNOR, BY MESNE ASSIGNMENTS, TO TRIUMPH VOTING MACHINE COMPANY, A CORPORATION OF NEW JERSEY.

VOTING-MACHINE.

1,080,014.

Specification of Letters Patent.

Patented Dec. 2, 1913.

Application filed January 2, 1906. Serial No. 294,067.

To all whom it may concern:

Be it known that I, WILLIAM J. LAUSTERER, of Jamestown, in the county of Chautauqua, State of New York, have invented 5 certain new and useful Improvements in Voting-Machines; and I do hereby declare the following to be a full, clear, and exact description of the same, reference being had to the accompanying drawings, forming a 10 part of this specification, and to the reference-numerals marked thereon.

My present invention relates to voting machines and particularly to those of the 15 class embodying indicators or keys adapted to be placed by the voter into coöperative relation with the actuators or operating parts of registers, and the registers whose indicators are left in voted position are subsequently operated by the movement of other 20 parts such as an actuating handle or curtain lever, and it has for its objects to provide means for automatically, accurately and fully positioning the indicators which have been moved far enough to indicate the voter's 25 choice, prior to registration so as to prevent the loss of votes intended to be cast, but which might otherwise not be counted.

The machines of the class to which my 30 invention is applied have been illustrated in numerous patents to A. J. Gillespie, the form of register employed being shown in Letters Patent to Gillespie No. 799,556, but the particular arrangement of the parts in the present application is different from that 35 in the patent.

In the accompanying drawings: Figure 1 is an elevation of a part of the mechanism of a voting machine viewed from the rear. Fig. 2 is a cross section on the line 2—2 of Fig. 1, looking in the direction of the arrow. Fig. 3 is a detailed perspective view of a 40 portion of what I term "boosting" bar. Fig. 4 is a sectional elevation showing the relation of the boosting bar, interlocking 45 strap, key and pallet bar.

Similar reference numerals in the several figures indicate similar parts.

My present invention is shown herein as applied to a machine of a type described in 50 patents of A. J. Gillespie and others, but it is understood, of course, that it may be applied to any other type of machine.

In the accompanying drawings reference numeral 1 refers to the indicators or keys 55 by means of which the voter indicates his

vote, said keys being pivoted and adapted to engage with the pallet bars 2 carried in the register casings or channels 3 in turn mounted in the register frame 4. The registers are substantially of the same type as 60 that described in the patent to A. J. Gillespie No. 799,556 in which the reciprocation of the register frame toward and from the support for the indicators causes the pallet bar to operate on its register. 65

Connected with the indicators or keys 1 are the interlocking straps 5, having at their lower end the interlocking wedges 6 coöperating with abutments and blocks in a guide and constituting interlocking mechanism. 70 At a suitable place in each of said straps is cut the recess 7 in which is left a tooth 8. Mounted in the machine frame and at a suitable and convenient distance below the teeth 8 of the straps is provided an oscillatory shaft 9 on which are carried cranks 10, and these cranks carry a boosting bar 11, which in the present case consists of a flat bar 12, having projections to form suitable bearings on the cranks 10 and at its upper 75 edge is reinforced by an angle iron. One or more springs 14 are provided on the boosting bar connecting it with the cranks 10, by means of which it is pressed forward toward the interlocking straps. The edge of the 80 boosting bar is held out of contact with the straps by the guides 14' arranged at the ends of the machine, one being shown in Fig. 3, which guide 14' has a step 15 therein, so placed as to delay the inward movement of 85 the bar until it has passed the teeth 8 of all of the straps that have not been moved and are not completely interlocked, it being the intention of this boosting bar to raise only 90 those straps and indicators to voted position which had been completely and properly interlocked, but may not have quite reached the position from which they will certainly operate the pallet bars of their registers. 95

It is obvious that this boosting of the indicators or keys incompletely operated, must be done quickly before the boosting of the keys will be prevented by the forward movement of the pallet bars, due to the operation of the register frame, and for this purpose I provide on the shaft 9 a crank or lever 16 having a pin 17 thereon engaging with the cam slot 18 in the cam plate 20 pivoted at 21 to the casing as shown in Fig. 2. The cam plate or lever 20 is driven by the vertically- 100 105 110

moving bars 19 (only one being shown), which form part of or are connected to the mechanism which reciprocates the register frame 4 toward and from the indicators to operate the registers, and are also connected to the resetting bar 22. In the present embodiment the frame reciprocating mechanism embodies levers 23 having pins 24 operating in cam slots 25 in the sides of the register frame, the bars or rods 19 actuating these levers when moved vertically by the barrier operating mechanism. The cam slot in the plate or lever 20 is so formed that as the lever is moved downwardly, the lower portion will first cause the quick upward movement of the boosting bar, carrying with it the indicators and straps whose projections 8 are above the level of the shoulders 15 on the guides 14, carrying these indicators to fully voted position, and then the remainder of the downward movement will move the boosting bar to its lowermost position again. This quick upward movement of the bar is accomplished at the beginning of the movement of the operating lever which operates the bars 19 and the register frame and before the register frame has moved far enough to prevent the upward movement of the straps or rods. The employment of this means for insuring the complete operation to voted position of the keys is found to be advantageous in that it effectually prevents the loss of votes which were intended to be cast.

35 I claim as my invention:

1. In a voting machine, the combination with movable ballot indicators, registers co-operating therewith and interlocking mechanism with which the indicators co-operate, 40 of a member for actuating to full voted position the indicators operatively engaged with the interlock, means for operating the registers corresponding with the indicators thus operated and connections between said 45 means and member for moving the latter to operate and release the indicators prior to the operation of the registers.

2. In a voting machine, the combination with movable ballot indicators, straps or 50 rods connected thereto having projections, registers with which said indicators co-operate, means for actuating the registers whose indicators are left in voted position, of a movable member co-operating with the 55 projections on the straps for moving partially-operated indicators to voted position and connections between the actuating means and member for operating the latter before the operation of the registers.

60 3. In a voting machine, the combination with ballot indicators, rods or straps connected thereto having projections, and a movable bar adapted to co-operate with the projections, of a movable cam co-operating 65 medately with the bar to operate and re-

turn it by a single movement in one direction.

4. In a voting machine, the combination with ballot indicators, rods or straps connected thereto, and a movable bar adapted 70 to co-operate with the rods or straps to move them to voted position, of the register frame, registers thereon, means for operating the frame relatively to the indicators and connections between said means and the 75 bar for operating the latter.

5. In a voting machine, the combination with ballot indicators, rods or straps connected thereto, a movable bar adapted to co-operate with the straps when the latter 80 are partially operated, a pivoted arm connected to the bar and a movable cam co-operating with said arm to move the bar and straps and disengage the bar therefrom by a movement in one direction.

6. In a voting machine, the combination with the indicators and the straps connected thereto, the relatively movable register frame, and the registers thereon corresponding to the indicators, of the shaft, the reciprocating bar connected thereto co-operating medately with the indicators, the arm on the shaft, the oscillatory cam with which the arm co-operates and connections between the cam and the register frame.

7. In a voting machine, the combination with the indicators, and the straps connected thereto, of the reciprocating bar adapted to co-operate with the straps, during a portion of its movement, guides for the bar and the movable cam actuating and returning the bar during a movement in one direction.

8. In a voting machine, the combination with the indicators and the straps connected thereto, of the shaft having the arm thereon, the bar connected to the shaft and adapted to co-operate with and operate the straps when moved in one direction and the movable cam plate engaging the lever on 110 the shaft to actuate the latter.

9. The combination with the indicators, the straps connected thereto, the movable bar adapted to co-operate with the straps, the oscillatory shaft connected to the bar, 115 and the lever having the cam thereon engaging the shaft, of the vertically-movable rods connected to and co-operating with the cam lever to actuate it, the registers and the register frame actuated by the rods.

10. In a voting machine, the combination of a movable ballot indicator, a register to co-operate therewith, means operable independently of the movement of the indicator for operating the register and means attached to the ballot indicator at a certain point and moving substantially parallel to the movement of the point of attachment, and means for co-operating with said means for moving the indicator when partially op-

erated into full coöperative relation with its register.

11. The combination in a voting machine of ballot indicators, arranged in rows and 5 movable into and out of voted position, straps or rods connected thereto having projections thereon, a bar extending parallel to said rows of keys and being movable side-
wise to engage with the projections on the

straps of any such keys as have been par- 10 tially operated to a predetermined extent and move the keys connected thereto into full voted position.
